UNITED STATES PATENT OFFICE.

ERNEST D. ANDERSON, OF NEW YORK, N. Y.

PACKING MACHINE.

Application filed November 28, 1925. Serial No. 71,971.

In packing numerous similar articles in boxes or cartons for sale, such as packages of candies and the like, it is desirable that designations, such as trade-marks, trade names, brands, flavors, etc., on the packages shall be exposed to view in a faced position in an orderly manner, so that purchasers may readily observe, in the boxes or cartons, the designations, etc., on the packages, or 10 the different flavors or characteristics of the goods to select from.

The object of my invention is to automatically pack or charge a number of articles or packages of goods in boxes or containers in such a way that the designations aforesaid will appear to view in a faced position, whereby a purchaser may readily observe the markings on the goods. Some 15 goods, such as candies, lozenges and the like, are sold in packages containing a number 20 of the candies or lozenges side by side and enclosed within a label upon which the designations and flavor of the candies or lozenges appear, and in accordance with my invention such labeled packages may be expeditiously charged into appropriate boxes 25 or cartons with a designation on the wrappers in faced position.

In carrying out my invention I provide 30 means to supply articles successively to means adapted to face or rotate such articles into a corresponding relationship successively with respect to the location of a designation thereon and as respects their final 35 position of deposit, in conjunction with means to transfer such articles successively for insertion in a box or carton, as in a position side by side therein, with the designations on the articles uppermost or in faced 40 position to be observed while within the box or carton.

My invention further comprises novel 45 details of improvement that will be more fully hereinafter set forth and then pointed out in the claims.

Reference is to be had to the accompanying drawings forming a part hereof, where in—

Fig. 1 is a side elevation of a machine 50 embodying my invention;

Fig. 2 is a side elevation of a portion of the machine showing parts in a different position from that shown in Fig. 1;

Fig. 3 is an enlarged cross section partially on the plane of line 3, 3, in Fig. 1;

Fig. 3^a is a detail side view illustrating an article held by grippers for deposit; Fig. 4 is a detail section substantially on the plane of line 4, 4, in Fig. 3;

Fig. 16^a is a partly sectional plan view of the article rotating devices;

Fig. 17 is a cross section substantially on the plane of line 17, 17, in Fig. 16;

Figs. 18 and 19 are perspective details of the receiver for the articles to be assembled;

Fig. 20 is a perspective view illustrating the parts in position for introducing the assembled articles into a box or carton; 95

Fig. 21 is a cross sectional view illustrating the entry of the assembled articles into a box or carton; and

Fig. 22 is a perspective view illustrating the box or carton containing the assembled articles.

Similar numerals of reference indicate corresponding parts in the several views.

Articles or packages of goods, indicated at A, to be packed in boxes or cartons, indicated at B, may be of any well known or desired variety having labels A' secured around the goods, (Fig. 5), as by means of suitable adhesive in any well known way. I 105

make use of the exposed or projecting edge portions α of the labels on the articles or packages of goods to determine the final faced positions of the desired designations A^2 , such as a trade-mark, trade name, brand or the like on the articles when packed in the boxes or cartons B, (Figs. 3, 3^a and 5). In the example illustrated in the accompanying drawings the articles or packages 10 of goods A are assumed to be of the variety in which a plurality of candies or lozenges are placed side by side and enclosed in a wrapper D, as of tin foil, around which the label A' is secured, (Fig. 5), such as illustrated in my Letters Patent No. 1,516,902, granted November 25, 1924. The articles or packages of goods A may be made in any desired or well known way, and may be delivered into position to be packed in accordance with my present improvements, such as upon a support or retainer 1 secured to spaced uprights 2 extending from arms or a bracket 3, which may be supported in the machine frame in any suitable way, (Figs. 1, 3 and 16^a). In Fig. 1 I have illustrated a portion of the wrapping and labeling machine disclosed in the aforesaid Letters Patent, at the delivery end thereof, 25 for the wrapped and labeled candies, the main frame 4 of which supports the arms or bracket 3, (Fig. 1).

In the example illustrated, (Fig. 1), a conveyor or belt 5 receives the wrapped and labeled articles A from the wrapping and labeling machine, wherein the labels are applied upon the wrapped packages or articles by means of the rollers 165, 166, the latter being carried by rock arms 167 on shaft 168, whereby when the packages have 30 been labeled the roller 166 will move away from roller 165 to release the labeled packages to be transferred to the conveyor 5, such as by being deposited in a delivery chute 172 of the wrapping and labeling machine, the delivery end of which chute extends over the conveyor 5 for delivering the wrapped articles thereto. The labeling devices described and illustrated in Fig. 1 are similar to those set forth in my aforesaid Letters Patent, to which reference is made for a more full description of suitable wrapping and labeling means for the production of the wrapped and labeled articles A. The wrapped and labeled articles A 35 may be produced in any other well known or desired way, and may be fed to the conveyor 5 in any suitable way, or manually. The conveyor belt 5 may be operated step-by-step, as in consonance with the successive labeling of the articles, by means of a ratchet wheel 6 secured upon the shaft 7 of the roll 8 at the delivery end of conveyor 5, over which the endless conveyor 5 travels from the inner supporting roll 9, shown located beneath the delivery end of

chute 172, (Fig. 1). A lever 10 is rockably supported upon or with reference to shaft 7 and is provided with spring-pressed pawl 11 to cooperate with ratchet wheel 6, said lever being shown pivotally connected by 70 rod 12 with the link 132 that is pivotally connected with the reciprocal rod 130 and with rock arm 133 carried by shaft 134 supported by the frame of the wrapping and labeling machine, the arm 133 being pivotally connected with link 136 that is cooperative with cam 137 on shaft 100, driven by belt 100^a on wheel 100^b whereby when arm 133 is rocked the lever 10 will cause step-by-step operation of the conveyor 5 to feed the articles A to the retainer 1.

The retainer 1 is shown comprising plate-like member 1^a, (Figs. 5 and 6), to the delivery end of which is attached an abutment piece 1^b, as by means of screws 13, which abutment piece is shown provided with prongs or fingers 1^c extending through slots 1^d in the lower end of the retainer, the prongs or fingers being upwardly bent to extend in the path of the articles A as they roll along the retainer to act as a stop for the articles at the delivery end of the retainer.

I provide means to engage the articles A (on the retainer) and rotate them axially in such a way that the edges α of the labels A' will encounter, during rotation, one or more stops 13 which are freely journaled upon a rod 14 secured between the uprights 2, (Figs. 3 and 4), to stop rotation of the articles with their designations A² in a definite or faced position with respect to their final position of deposit. The stops 13 may be resisted by light springs 15 shown projecting from a strip 15^a that is secured by screws 16 to the hubs 17 that project from the uprights 2, which hubs retain the stops 13 from lateral displacement, (Figs. 3 and 5). Means for rotating the articles A are shown as follows: members 18, 18^a slidably supported in bearings or bores 19 in uprights 2 and located adjacent to opposite sides of the retainer 1 are adapted to engage the ends of articles A resting at the abutments 1^c, (Figs. 3 and 16^a), which members 18 are adapted to be advanced against the ends of the articles A to grip and rotate the same, and to be separated to release the articles. Shafts 20, 20', are rotative in the bores 19 and are longitudinally movable therein, such means being provided between the shafts 20, 20' and members 18, 18^a. The shafts 20, 20' are reduced at their inner ends at 20^a to enter bores in the adjacent ends of the members 18, 18^a, which members are provided with slots 21 receiving pins 22 extending from the reduced ends 20^a, (Fig. 3), and a clutch member 23 is slidable on the reduced end 20^a of each shaft 20, 20', to frictionally engage the adjacent end of the

corresponding member 18, 18^a. The clutch members 23 are provided with slots 24 receiving pins 25 extending from the reduced ends 20^c, and springs 26 of a light expansion nature are interposed between the shoulder 27 on the shaft and the clutch member 23, normally tending to force the latter against the corresponding member 18, 18^a, the pins and slots limiting the inward sliding of said members and clutches 23 toward the interposed article A, (Fig. 3). The shafts 20, 20^c are adapted to be reciprocated back and forth for each article A to be rotated, for which purpose levers 28, 28^a are pivotally supported at 29 upon brackets 30 extending laterally from the uprights 2, (Figs. 6, 16 and 16^a), the corresponding ends of said levers being forked at 28^b, (Fig. 3), to receive the adjacent ends of the shafts 20, 20^c, and to operate against spaced stops 31 on said shafts. The opposite end of each lever 28, 28^a is forked and operated by means of a pin 32 on a sliding rod 33, 33', carried in bearings 34 upon uprights 2, which rods are adapted to be reciprocated, (Figs. 6 and 16^a). A cam 35, 35^a for each rod is adapted to engage an abutment 36, 36' on the corresponding rod 33, 33', spring 37 located between and cooperating with said abutments, serving with an expansion pressure normally to retain the stops 36, 36' against the cams 35, 35^a. The inner ends of rods 33, 33' are shown slidable within tube 37' that is encircled by the spring 37, (Fig. 16^a). The cams 35 and 35^a are shown attached to a transverse bar 38 connected with link 12, (Figs. 1, 6 and 16^a), whereby as the latter is reciprocated the cams will be reciprocated for alternately forcing the members 18, 18^a against the ends of an article A located at the retainer abutment 1^b and releasing the article, and so on for successive articles fed to the retainer. The shafts 20, 20^c are provided with gears 39, 39^c that are in mesh with corresponding gears 40, 40^c, located on opposite sides of the machine, (Figs. 3, 16 and 16^a), which gears 40, 40^c are secured upon a shaft 41 journaled in bearings on the uprights 2, said shaft being shown provided with a sprocket wheel 42 receiving drive chain 43, which may be driven by a sprocket wheel 44 secured on shaft 100 of the wrapping and labeling machine, indicated in Fig. 1, which shaft may be driven as set forth in my aforesaid Letters Patent.

In accordance with the parts so far described it will be understood, and the timing of the parts will be such, that each time an article A rests at the retainer parts 1^a, 1^c the continually rotating members 18 will be advanced (by the retreat of cams 35, 35^a in the direction of the arrow in Fig. 16^a and the expansion of the spring 37) to engage the corresponding ends of said article, and

the latter will be rotated through the medium of the pressure of the relatively light springs 26. When the edge *a* of label A' engages the stop or stops 13 the rotation of such article will be arrested and continued rotation of the shafts 20, 20^c, without further rotating the article A located between the members 18, 18^a, will be permitted by the slipping of the frictional surfaces between said members and the corresponding clutch member 23 temporarily, and thereupon the cams 35, 35^a will advance reversely to the arrow in Fig. 16^a to operate the rods 33, 33', to cause tilting of levers 28, 28^a and thereby effect outward movement of the shafts 20, 20^c and withdrawal of the members 18, 18^a from the ends of said article A to release it.

When the article A has been positioned with its projection or label edge *a* against the stop or stops 13, (Fig. 5), in manner stated, the designation on the article and its label will have been brought to a definite faced position with respect to the position in which the article A will finally be faced within the box or carton B. When the members 18, 18^a have been withdrawn from the article A suitable gripping means will grasp such article and remove it from the retainer 1 to a place of deposit for insertion in the box or carton, with the designation on the article in position to be observed. I have illustrated a pair of grippers comprising spaced rockable arms 45 carried by spaced shafts 46 below the retainer, rockably supported in bearings in brackets 2^a depending from the arms or brackets 3, (Figs. 1 and 3), in position to pass the ends of the articles A located upon retainer 1. The arms 45 are provided with resilient gripping fingers 45^a adapted to grasp the corresponding ends of the articles A successively as the arms 45 are rocked, said fingers being shown curved at the free ends for conveniently engaging the ends of the articles A. The arms 45 are provided with segmental gears 47 in mesh with racks 48, which are carried by bars 49 adapted to be reciprocated for rocking the arms 45. In the example illustrated in Fig. 1, the bars 49 are connected to the reciprocative bar 64, which may be reciprocated in any suitable or well known way, and corresponds to bar 64 and may be operated as illustrated in my Letters Patent aforesaid, by means of rock arm 65' journaled on shaft 44' and cooperative with a cam 66' on shaft 22', (Fig. 13).

In accordance with my invention one or more series of articles A may be deposited in a row or side by side in a box or carton B, such as illustrated in Fig. 22. At the time that the arms 45 rock toward an article A upon retainer 1 the members 18, 18^a will have been withdrawn from said article to permit the arms 45 and their fingers 45^a to

pass between the adjacent corresponding ends of said articles and said members. Means may be provided to keep the articles A from rolling backwardly along retainer 1 at such time and for the purpose I have illustrated the following devices. A presser finger 50 is mounted to rock over the articles A when at the delivery end of the retainer, which finger is journaled upon a pivot 51 carried by one of the uprights 2, (Figs. 7, 8, 9 and 12). A link 52 is pivotally connected with a projecting end portion 50^a of finger 50 and with the lever 28 for rocking the finger. The arrangement is such that 15 when members 18, 18^a move away from article A on the retainer 1 the finger 52 will be advanced to engage such article and resist rearward movement of the same along the retainer by the spring fingers 50 when 20 they advance to engage the article, and such fingers may withdraw the article A as they advance to deposit the same.

In order to lay the articles A side by side in a row for depositing in a box B I provide the receiver, or holder indicated generally at 53, shown in the form of a skeleton frame open at top and bottom and comprising spaced side bars 53^a connected by spaced rods 54 at the lower part, said side bars having upstanding spaced projections 53^b which are provided with upwardly disposed curved springs 55 riveted to projections 53^b. The springs 55 are of relatively light tension to permit the articles A to be inserted therebetween and be retained suspended by such springs, (Fig. 11).

Each time that the arms 45 descend with an article A and deposits the same between opposing springs 55 in receiver 53 the fingers 45^a are to be spread to release the articles. Means to spread said fingers are illustrated in Figs. 13 and 14 as follows: Reciprocatative bars b are slidably supported in guides c carried by the main frame and have inclined end portions b' adapted to engage the inner surfaces of the fingers 45^a, outside of the receiver 53, in such a way that when the fingers 45^a have deposited an article in the receiver the bars b will advance and their inclined surfaces b' will engage said fingers and spread them apart and release them from the ends of the articles so that the articles will be deposited in the receiver in definite positions with their designations uppermost. After the arms 45^a have risen from the receiver the rods b will be retracted ready for a further advance on depositing the next article in the receiver, and so on for each article. Any suitable means may be provided for reciprocating the rods b, such as by means of a cam d secured on shaft 22' and adapted to operate a projection or roller e extending from an arm f pivotally supported at g on the main frame and shown provided with a link h

pivots connected with said arm and with the rods b, (Fig. 13).

In the example illustrated it will be assumed that the articles A will be placed in a row or series in each box B, and a plurality of such rows of articles may be superposed therein. The receiver 53 is mounted in such a way as to be moved longitudinally step-by-step for successive deposits of articles A therein, such as ten steps, and I also provide means for raising and lowering the receiver 53 to different levels to accommodate superposed rows or series of articles A. To provide for the articles in a row there are projections 53 and springs 55 spaced apart on each side of the receiver in opposing pairs, A base 56 is provided with pairs of uprights 57 on opposite sides, having rollers 58 upon which lateral flanges 59^a extend from a reciprocative frame 59 and rollers 60 on the uprights 57 bear upon the flanges 59^a for guiding the frame 59, (Figs. 1, 2 and 17). The frame 59 carries uprights 61 in pairs spaced apart for suspending the receiver 53. The uprights 61 carry rock arms or levers 62 that are pivotally connected at their inner ends with the extended projections 53^a of receiver 53, the outer ends of which arms are pivotally connected by links 63 with bell-crank levers 65 pivotally supported upon the corresponding uprights 61 and connected together by a link 66, to operate in unison, (Figs. 1 and 2). A spring 67 connected with one of the bell-cranks 65 and with the frame 59 counterbalances the receiver and the parts connected therewith. A projection 62^a from one of the arms 62 is adapted to engage spaced stops 61^a upon one of the arms 61 to retain said arm 62 in different positions of adjustment. The stops 61^a may be spring pressed of any known variety. The arrangement just described is such that when one of arms 62 is tilted, as from the position shown in Fig. 1 to the position shown in Fig. 2, the receiver 53 will be moved from an elevated position (in which it receives one row of articles A) to a lowered position for the deposit upon such articles of a superposed row of articles, and the receiver will be raised for a subsequent series of articles. Means are provided for moving the frame 59 in opposite directions, as to the right in Fig. 1, to receive the lower or first row or series of articles A, and to the left in Fig. 1 to receive the upper or second row or series of articles A, for which purpose mechanism is illustrated as follows: From the frame 59 spaced brackets 68 depend and support lower and upper vertically spaced racks 69, 70, which are united together by intermediate bars 71 which are vertically slotted at 72 and receive headed pins or screws 73 projecting from the brackets 68, for slidably guiding the racks in a vertical direction and so that the racks

will travel back and forth with frame 59, (Figs. 1, 2 and 15). The racks and the bars 71 may be formed in a unitary structure. At 74, 75 are bell-crank levers pivotally supported upon base 56 at 76, 77. One arm of each bell-crank lever is provided with a projection 74^a, 75^a operative in a longitudinal slot 78 in the material of the lower rack 69 for slidably supporting and for raising and lowering said racks, and the bell-crank levers 74, 75 are pivotally connected together by a bar 79 so that they will operate in unison. Between the racks is located a gear 80, (Figs. 15 and 17), adapted to be alternately engaged by the racks 69 and 70 for causing traverse of frame 59 and with it the receiver 53 in opposite directions. The gear 80 is secured upon a shaft 81 journaled upon a bracket 82 carried by base 56, (Fig. 17). Upon said shaft a cam 83 is secured and adapted to cooperate with a projection or roller 84 at the end of the upstanding arm of bell-crank 74 for rocking said bell-crank to raise and lower the racks and frame 59, (Figs. 15 and 17). A ratchet wheel 85 is secured on shaft 81 and is adapted to be actuated by a pawl 86 carried by a rock arm 87 journaled upon said shaft. The rock arm 87 is pivotally connected with a link 88 that connects with a lever 88' and with rod b to be reciprocated by the rod b, (Figs. 1 and 13).

The first position of receiver 53 is elevated to receive a first row or series of articles A, as in Fig. 1, and I provide means to lower said receiver, as to the position shown in Fig. 2, to receive the second or superposed layer of articles A, for which purpose devices are arranged as follows: One of the arms 62 is provided with a projection or roller 62^a adapted to enter the forked end 62^b of a rock arm 62^c that is pivotally supported on the shaft 134 and provided with an extending portion 62^d adapted to be operated by a suitable cam 62 carried by shaft 100, (Fig. 1). The arrangement is such that when receiver 53 has been moved to the right in Fig. 1 such a distance that the projection 62^a will enter the fork 62^b and the receiver comes to rest when ten articles have been deposited therein the arms 62^c will be operated in an upward direction to cause tilting of the corresponding arm 62 and thereby to effect depression of the receiver 53 to place it on a lower level, (Fig. 2). When the receiver moves to the left in Fig. 2 for the deposit therein of a second or superposed layer or row of articles A the projection 62^a will move away from the fork 62^b and cam 62^a may thereafter operate arm 62^c to again lower its fork in position to receive the projection 62^a after the receiver 53 has been raised in position to receive a lower layer or row of articles A, and so on for each two rows of

articles deposited in the receiver. Means for raising the receiver 53 will be described hereinafter.

Assuming that there are ten articles A to be deposited in each row the ratchet 85 may be provided with twenty two teeth and the cam 83 is appropriately organized in such a way that when the rack 69 is in mesh with the gear 80 the receiver will be elevated. The rack will be fed step-by-step for ten teeth of the ratchet for the deposit of ten successive articles A in receiver 53, which will travel to the right in Fig. 1, and then on the next step of the ratchet the cam 83 will operate the bell-crank 74 to cause the rack and the frame 59 to be lowered to unmesh the rack 69 from gear 80 and to mesh rack 70 with gear 80, whereby rack 70 will cause traverse of frame 59 and receiver 53 to the left in Fig. 1 for depositing the second row of ten articles upon the first row step-by-step.

In order to deposit the articles A from receiver 53 into the box or carton B I provide a platform or support 89 located below the receiver, (Figs. 1 and 17), upon which the boxes or cartons B may be placed and raised within receiver 53 to push the cartons between the articles A and the springs 55 for charging the rows of articles into the cartons, (Fig. 20). The platform 89 is provided with a rack bar 90 guided in bearing 91 disposed upwardly from frame 59, (Figs. 1 and 17), which rack is in mesh with a gear 92 frictionally mounted on a rock shaft 93 journaled upon frame 59, (Figs. 1 and 17). The shaft 93 is provided with a handle or crank 94 which may be used by the operator for raising and lowering the platform 89. When the receiver 53 has been charged with the requisite number of articles A the shaft 93 will be rotated in such a way as to cause the platform with a carton thereon to be raised to pass between the articles A and the springs 55, (Fig. 20). A plunger 95, adapted to pass through receiver 53, is located over the latter and the platform 89, and is shown provided with a stem 95' that is guided in a bearing 61^a carried by one of the uprights 61, (Fig. 1). Said stem is movably connected with a lever 95^a pivotally supported at 61^b on bracket 61 and pivotally connected by a link 95^b with a crank arm 93' on shaft 93. The gear 92 is loose on shaft 93 to which shaft disks 92^a, 92^b are secured on opposite sides of the gear, a washer 92^c being interposed between the gear and disk 92^b to frictionally connect the gear with the shaft, (Fig. 16). Stop means limit the upward movement of platform 89, being shown in the form of a vertical slot 90^a in rack bar 90 receiving a pin 91^a carried by a bearing 91, (Fig. 17). The arrangement is such that when shaft 93 is rotated to

cause rising of the platform with a box the plunger 95 will operate upon the articles in the receiver to resist them. When the box has been properly inserted in the receiver, with the articles in the box, the rise of the platform will be stopped by the pin 91^a and continued rotation of shaft 93 will cause descent of the plunger 95 to push on the articles and cause them with the box to descend from the receiver, also pushing down the platform to its normal position (to receive another box), which is permitted by the slipping of the friction between the gear 92 and the washer 92^c. When the rotation of shaft 93 is reversed the gear 92 will not rotate, due to the slipping of the friction at washer 92^c, and the plunger 95 will be raised to the normal position over receiver 53. Each time the platform 89 rises it will engage the receiver 53 to raise it to position to receive another first row or series of articles for a succeeding box B. The shaft 93 may be connected with any suitable clutch of the machine, indicated at 93^a on a drive shaft 93^b, (Fig. 13), that will cause it to stop operation during the time that the box is being charged with the articles in the receiver and until the plunger 95 has been suitably raised.

30 The cartons or boxes may be charged with the articles directly by placing the former on the platform 89 and omitting the receiver 53 and plunger 95, or by inserting the cartons or boxes in the receiver before the articles are deposited by the fingers 45^a.

Having now described my invention what I claim is:

1. A machine of the character described comprising means to position articles bearing designations successively with their designations in a definite position with respect to their final position of deposit, means to deposit said articles with their designations in position to be observed, and means to move a series of deposited articles from one level to another level to receive a second row of articles upon the first row with their designations in position to be observed.
2. A machine of the character described comprising means to position articles bearing designations successively with their designations in a definite position with respect to their final position of deposit, receiving means for the articles, means to successively deposit articles in the receiving means, means to move the receiving means step-by-step for said successive articles, and means to move the receiving means from one level to another level to receive a second row of articles upon the first row with their designations in position to be observed, said moving means being operative to move said receiving means in a direction reverse to its direction during depositing of the first row of articles therein.

3. A machine of the character described comprising means to retain articles bearing designations, means to rotate said articles and stop them with their designations in a definite position with respect to their final position of deposit, and means to deposit said articles with their designations in position to be observed.

4. A machine as set forth in claim 3, provided with means to receive a series of articles, and provided with means to move deposited articles step-by-step for assembling of the articles in a row side by side with their designations in like positions.

5. A machine of the character described comprising means to retain articles bearing designations, means to rotate said articles and stop them with their designations in a definite position with respect to their final position of deposit, means to deposit said articles with their designations in position to be observed, means to receive a series of articles, means to move deposited articles step-by-step for assembling of the articles in a row side by side, and means to move said receiving means from one level to another level to receive a second row of articles upon the first row with their designations in position to be observed.

6. A machine of the character described comprising means to rotate articles bearing designations and provided with projections, stop means in the path of the rotating projections to stop said articles with their designations in a definite position with respect to their final position of deposit, and means to deposit said articles with their designations in position to be observed.

7. A machine as set forth in claim 6, in which the means for rotating the articles includes means to release the articles from rotational force.

8. A machine of the character described comprising means to rotate articles bearing designations and provided with projections, stop means in the path of the rotating projections to stop said articles with their designations in a definite position with respect to their final position of deposit, said means to rotate the articles being movable toward and from the latter to engage and release the articles, and means to deposit said articles in position to be observed.

9. A machine of the character described comprising means to rotate articles bearing designations and provided with projections, stop means in the path of the rotating projections to stop said articles with their designations in a definite position with respect to their final position of deposit, said means to rotate the articles including a spring actuated clutch to rotate the articles and release them from rotational force when their projections engage the said stop, and

means to remove the articles from relation to the rotating means and deposit said articles with their designations in position to be observed.

- 5 10. A machine of the character described comprising means to rotate articles bearing designations and provided with projections, said means including one or more rotative members movable relatively to the articles 10 to engage and release the same, a retainer for the articles, stop means to engage the projections of the articles to stop them with their designations in a definite position with respect to their final position of deposit, and 15 means to remove the articles from the retainer when released from their rotating means and deposit said articles with their designations in position to be observed.
11. A machine of the character described 20 comprising means to rotate articles bearing designations and provided with projections, said means including one or more rotative members movable relatively to the articles to engage and release the same, a retainer 25 for the articles, stop means to engage the projections of the articles to stop them with their designations in a definite position with respect to their final position of deposit, and reciprocal means to engage the articles 30 when positioned by the stop means and deposit said articles with their designations in position to be observed.

12. A machine as set forth in claim 11, in which the reciprocal means includes 35 fingers adapted to engage said articles, said fingers being carried by rockable arms to move the fingers from article receiving to article depositing position, and vice-versa, and means to actuate said arms.

- 40 13. A machine of the character described comprising means to retain articles bearing designations and provided with projections, stop means for said articles to position their 45 designations with respect to their final position of deposit, continuously rotative means for rotating said articles, devices to cause said rotative means to engage and disengage said articles, and means to grip said 50 articles and remove them from the retainer when they have been released from the rotating means and to deposit said articles with their designations in position to be observed.

55 14. A machine as set forth in claim 13, provided with means to remove deposited articles step-by-step for assembling of the articles in a row side by side with their designations in like position.

- 60 15. A machine of the character described comprising means to position articles bearing designations with their designations in a definite position with respect to their final position of deposit, gripping means to receive said articles and deposit them successively with their designations in position

to be observed, receiving means for said articles, means to move said receiving means step-by-step for successive articles deposited therein, and means to release each of the articles in said receiving means.

- 70 16. A machine of the character described comprising means to position articles bearing designations with their designations in a definite position with respect to their final position of deposit, gripping means to receive said articles and deposit them successively with their designations in position to be observed, a receiver for the articles open at the top and bottom and provided with means to retain the articles suspended therein, means to move said receiving means step by step for receipt of articles successively therein with their designations uppermost, and means to insert a box within the receiver for charging the articles therein.

75 17. A machine as set forth in claim 16, in which the means for moving the receiver includes means to advance the receiver step-by-step a definite number of times in one direction and step-by-step a definite number of times in an opposite direction, with means to move the receiver from one level to another level for depositing rows of articles in the receiver one upon another.

- 80 18. A machine of the character described comprising means to position articles bearing designations with their designations in a definite position with respect to their final position of deposit, gripping means to receive said articles and deposit them successively with their designations in position to be observed, a receiver for the articles open at the top and bottom and provided with means to retain the articles suspended therein, a pair of spaced racks connected with the receiver, a gear adapted to mesh with said racks alternately, means to move one rack out of mesh and the other rack into mesh with said gear, and vice versa, 100 means to rotate said gear step-by-step, said receiver being connected with the racks to be moved therewith from one level to another for receiving first one row of articles and then another row of articles thereon 105 during corresponding travel of the receiver, and means to insert a box within the receiver for charging the articles therein.

110 19. A machine of the character described comprising means to position articles bearing designations with their designations in a definite position with respect to their final position of deposit, gripping means to receive said articles and deposit them successively with their designations in position to be observed, a receiver for the articles open at the top and bottom and provided with means to retain the articles suspended therein, a pair of spaced racks connected with the receiver, a gear adapted to mesh 115 with said racks alternately, means to move 120

125 130 135 140 145 150 155 160 165 170 175 180

one rack out of mesh and the other rack into mesh with said gear, and vice-versa, means to rotate said gear step-by-step, said receiver being connected with the racks to be moved therewith from one level to another for receiving first one row of articles and then another row of articles thereon

during corresponding travel of the receiver, a platform movably supported below the receiver to be moved toward and from the same with a box thereon, and means to move the platform toward and from the receiver at will.

ERNEST D. ANDERSON.
